United States Patent Office.

W. T. SEARS AND WILLIAM EDSON, OF BOSTON, MASSACHUSETTS,
ASSIGNORS TO W. T. SEARS.

Letters Patent No. 94,245, dated August 31, 1869.

VENTILATOR.

The Schedule referred to in these Letters Patent and making part of the same.

To all whom it may concern:

Be it known that we, W. T. SEARS and WILLIAM EDSON, of Boston, in the county of Suffolk, and State of Massachusetts, have invented a certain new and useful improved Window-Ventilator; and we do hereby declare that the following is a full and exact description thereof, reference being had to the accompanying drawings, and to the letters of reference marked thereon.

The nature of our invention consists in so arranging a casing, in connection with the lower part of a window, and a heat-radiating apparatus, that when the window is raised within certain limits the fresh air thus admitted is forced into contact with the heating-surface, and thus warmed before it can enter into the room.

To enable others skilled in the art to make and use our invention, we will proceed to describe its construction and use.

Drawings.

Figure 1 is a perspective view of the interior of a room, showing a window with our improvement attached.

Figure 2 is a section of the same.

Figure 3 represents, in dotted lines, a modification of our invention.

Our invention may be constructed in a variety of ways, but the one represented in the drawings shows the general principle.

Let D D' D'', &c., represent the heat-radiator, which may consist of a system of pipes, as represented in the drawings, or of any suitable radiating-device.

A, B, C represent a box-casing, arranged as shown in the drawings, so that, if the sash S is raised, the space a b, fig. 2, will allow external air to flow in, and, coming in contact with the radiators D D' D'', &c., will be warmed, after which it will pass into the room.

H, fig. 2, represents a wire-cloth screen.

The amount of air to be admitted is regulated by the sash S, which may be raised or lowered at will.

What we claim as our invention, and desire to secure by Letters Patent of the United States, is—

The air-box A B, in combination with the window W and the heating-surface D D' D'', substantially as described, and for the purpose set forth.

W. T. SEARS.
WILLIAM EDSON.
